DESIGN FOR A SUNDIAL

Murray T. Swisher, Clairton, Pa.

Application June 24, 1939, Serial No. 85,665

Term of patent 14 years

To all whom it may concern:

Be it known that I, Murray T. Swisher, a citizen of the United States, residing at Clairton, in the county of Allegheny and State of Pennsylvania, have invented a new, original, and ornamental Design for Sun Dials, of which the following is a specification, reference being had to the accompanying drawing, forming part thereof.

I claim:

The ornamental design of a sun dial, as shown.

MURRAY T. SWISHER.
